APPARATUS FOR APPLYING BANDS
ON CONTAINERS

Hallward F. Nygard, Madison, Wis., assignor to
The Celon Company, Madison, Wis., a corpora-
tion of Wisconsin

Application April 2, 1934, Serial No. 718,597

13 Claims. (Cl. 226—80)

This invention relates to the method of applying bands on containers, such as bottles and the like, and to apparatus for applying said bands.

The primary object of the present invention is to provide a new and novel method of applying bands to containers, such as bottles and the like, and an apparatus used in connection with the method.

Another object of the invention is to provide a method for applying regenerated cellulose bands in their wet state to containers, such as bottles and the like, whereby the bands may be rapidly and easily applied in position over the necks of the containers or bottles.

Another object is to provide an apparatus about which a part thereof bands are placed and then spread or extended a predetermined distance by the said apparatus to permit the apparatus to easily, quickly and efficiently position the band about the neck of the container.

A still further object is to provide an apparatus having an extensible portion about which hydrated cellulose bands are placed and extended a distance sufficient to permit the apparatus or tool to be easily and quickly inserted about the neck of a bottle whereby the band will be inserted over the neck of the bottle when the device is withdrawn.

Still another object of the invention is to provide the method of placing hydrated regenerated cellulose bands about the neck of a bottle which consists in inserting a wet band about collapsible jaws of a device, inserting the jaws over the neck of a bottle whereby the jaws will be arranged between the neck of the bottle and the exteriorly positioned band, tripping the device so as to bring the jaws together and then withdrawing the collapsed jaws from the bottle so that the band will be in proper relative position in respect to the bottle neck, the band shrinking tightly about the neck of the bottle while being dehydrated.

A still further object of the invention is to provide continuously operating mechanism containing a plurality of devices about which hydrated regenerated cellulose bands are arranged whereby the necks of the bottles may be quickly inserted in a device as it moves to application position whereby a band will be placed about the neck of the bottle, the plurality of devices being movable constantly in position whereby a great number of bottles may have bands applied about the necks thereof within a very short space of time.

Another important object of the invention is the provision of an applicator for use in connection with applying seal bands on bottles whereby bands may be applied to bottles, the bands being actually smaller than the bottles would normally require as the applicator stretches the bands considerably and permits easy application thereof.

Numerous other objects and advantages will be apparent throughout the progress of the following specification.

The accompanying drawings illustrate a selected embodiment of the invention and the views therein are as follows:

Fig. 1 is a detail elevation, partly in section, 15 of a hand operated device for applying bands, such as hydrated regenerated cellulose bands, about the neck of a container, such as a bottle.

Fig. 2 is a detail elevation similar to Fig. 1 but at right angles thereto.

Fig. 3 is a detail elevation, partly in section, 20 showing the device in its expanded position to apply a band about the neck of a bottle.

Fig. 4 is a view similar to Fig. 3 showing the device tripped and ready to be removed from 25 the bottle neck.

Fig. 5 is a detail sectional view on the line 5—5 of Fig. 3.

Fig. 6 is a detail sectional view showing a band applied about the neck of a bottle and 30 over a revenue stamp, the revenue stamp being applied about the smaller transverse dimension of the bottle.

Fig. 7 is a detail elevation of one form of apparatus which may be continuously rotated and 35 carrying a plurality of band applicators whereby the production may be considerably increased.

Fig. 8 is a detail sectional view of the line 8—8 of Fig. 7.

Fig. 9 is a detail sectional view of a bottle 40 having a band applied about the neck thereof and over the revenue stamp, the stamp being positioned about the greater transverse dimension of the bottle.

The hand operating device or apparatus for 45 applying bands to the closure end of containers, such as bottles, is shown particularly in Figs. 1 to 6, and referring thereto 10 designates a handle provided with a vertical bore 11 through which a rod 12 extends. The upper end of the 50 bore 11 merges with a bore 13 of larger diameter. A cap 14 having a plunger end 15 is removably fastened to the rod 12, and a spring 16, arranged about the cap 14 and the upper end of the rod 12, is seated in the larger bore 13 and 55

urges the rod 12 in an upward direction. A ferrule 17 may be positioned in the bore 11, and a nut 18 threadedly engaging the lower end of the ferrule 17 is adapted to impinge the horizontal portion or yoke 19 between the bottom of the handle 10 and the nut 18 as clearly shown in the various figures, particularly Figs. 1 to 3. The yoke 19 is provided with downwardly extending pairs of spaced ears 20 and 21. Downwardly extending links 22 and 23 are pivoted to the pairs of ears 20 and 21 respectively as indicated at 24. Oppositely disposed arcuate jaws 25 and 26 are fastened to the lower ends of the links 22 and 23 by means of reinforcing elements 27 and screws 28. Links 29 and 30 have their outer ends pivotally connected at 31 to the downwardly extending links 22 and 23 respectively, and their inner ends pivoted to the rod 12 as indicated at 32. The yoke 19, the links 22 and 23 and their cross links 29 and 30 provide toggle mechanism controlling the operation of the jaws 25 and 26. The rod 12 extends downwardly a predetermined distance and in a position adjacent the jaws 25 and 26, there being a tripper end or knob 33 formed on the lower end of the rod 12.

When the plunger end 15 of the rod 12 is pressed downwardly, the rod 12 will move downwardly carrying with it the links 29 and 30. The downward movement of the links 29 and 30 spreads the links 22 and 23 and consequently the jaws 25 and 26 apart. The jaws therefore, when spread apart, will assume the position shown in Fig. 3, permitting the neck 34 of a bottle 35 to be received between or positioned within the jaws 25 and 26. The downward movement of the rod 12 is such that the links 29 and 30 will extend below their normal horizontal center line. This downward movement may be limited by ears 36 formed on the inner ends of the links 29 and 30 and these ears are adapted to engage the shaft or rod 12. The neck of the bottle is inserted a predetermined distance within the jaws 25 and 26 of the device to have a band 37 applied thereto.

Bands 37 are preferably made of hydrated regenerated cellulose and these bands are preferably shipped wet, that is, a plurality of bands are shipped in a container containing a fluid to keep the bands smooth and moist. When the bands are applied to articles they are applied in their wet or hydrated state, the bands tightly shrinking about the necks of the bottles when dehydrated. It is a relatively easy matter to apply a smooth set band about the neck of a bottle where a revenue stamp or seal is not applied over the closure 38 of the bottle. However, in cases where a stamp or seal 39 is applied over the closure 38 of the bottle, it is quite difficult as great care must be taken not to tear or mutilate the stamp or seal. Therefore when stamps or seals are placed over bottles, great care must be exercised. It has been found convenient and practical, therefore, to use a tool or device of the type just described to apply the bands in position about the necks of bottles and over the seals. In many instances for certain products the seals are required by statute and they must not be mutilated.

In carrying out the invention a band 37 is placed over the jaws 25 and 26 when the jaws are in the position shown in Fig. 1. The plunger end 15 is then pressed downwardly until the rod assumes the position shown in Fig. 3 at which time the links 29 and 30 will be beyond

their normal horizontal center line. The spacing of the jaws is such that a slight tension or expansion is placed on the bands and this tension counteracts the urging action of the spring 16 and holds the device in its extended position as shown in Fig. 3. The neck of the bottle is then inserted between the jaws 25 and 26 until the cap 38 of the bottle engages the plunger 33 at which time the engagement of the bottle with the end 33 is sufficient to move the rod 12 upwardly a predetermined distance to move the links 29 and 30 above their normal horizontal center line. In this latter position the spring 16 pulls the rod upwardly and consequently draws the links 22 and 23 inwardly to the position shown in Fig. 4. The jaws 25 and 26 will therefore engage the neck of the bottle as shown in Fig. 4. To retract the jaws a pressure is exerted at the points indicated at 40, Fig. 5, to hold the band to the bottle while the jaws are being slipped out of position. After the jaws have been removed, the bottle is permitted to stand until the band dries after which time the band will tightly shrink about the neck of the bottle in the manner shown in Fig. 6. A neat appearance is rendered to the bottle, the bottle is rendered ornamental, the seal or stamp is neatly and permanently positioned in place and the cap 38 of the bottle is locked in place and cannot be removed. If desired, the band 37 may be applied to the neck of the bottle before the stamp or seal 39 is applied. However, a much neater and attractive looking package is obtained if the seal is applied to the bottle before the band is put in place.

In Figs. 7 to 9 inclusive there is shown continuously operating apparatus for applying bands to bottles. In these views there is shown a support 50 having a transverse axis or axle 51 upon which there is rotatably mounted a wheel 52. A plurality of jaws 25 and 26 extend outwardly radially from the outer peripheral surface of the wheel 52. These devices, which are mounted about the periphery of the wheel, may be exactly the same in construction as the device shown in Figs. 1 to 6 except that instead of using a handle 10, the wheel 52 is employed. The rod 12 extends through the wheel with the plunger 15 on the inner side as clearly shown in Figs. 7 and 8. Also, instead of manipulating each device manually to stretch the bands when they are applied over the jaws 25 and 26, a rigidly mounted cam 53 may be mounted in a position to successively engage the ends 15 as the wheel 52 rotates. The wheel 52 is rotated by a motor 54, a chain 55 and reduction gearing 56.

In operation the bands 37 are successively applied onto the device by an operator standing at the left-hand side of the machine, these bands being placed on each device as it moves to applying position. During the rotative movement of the wheel, the bands 37 will be stretched when the end 15 of the rod 12 engages the cam 53. The tension on the band on the jaws 25 and 26 holds the jaws 25 and 26 in their extended position. At the right-hand side of the machine, Fig. 7, an operator inserts the bottle 35 between the open jaws 25 and 26, and in inserting the neck in position, the plunger end 33 is engaged by the bottle with sufficient force to move the rod 12 inwardly a predetermined distance at which time the spring 16 will move the jaws to closed position at which time the jaws, with respect to the band and bottle, will be in exactly

the same position as shown in Fig. 4. The operator handling the bottles therefore has nothing to do except move the neck of a bottle in position as a device comes in place and then, as soon as the device is tripped, withdraw the bottle with the band applied thereto.

In Fig. 9 the bottle 35 shows the seal 39 applied along the greater transverse dimension of the bottle, while in Fig. 6 the bottle is shown as having the stamp or seal applied about the smaller dimension of the bottle.

If desired, the spring means 60, Fig. 3, may be positioned relative the links 22 and 23 and their cooperating links 29 and 30 to assist in overcoming the urging action of the spring 16 to hold the device in its extended position, that is, the position shown in Fig. 3 when the links 29 and 30 will be moved below their normal horizontal center line.

20 The purpose of a band is to make an air-tight seal on a bottle, as the band shrinks by dehydration. A cellulose band from its normal diameter is susceptible of between 20% and 25% shrinkage. Naturally the tightest band that will 25 go on a bottle makes the best appearance and best seal after the band has shrunk. The use of the mechanism herein described permits the use of the band actually smaller normally than the bottle would require, as the applicator 30 stretches the band considerably and permits of easy application. When the applicator is withdrawn, the band does not immediately spring back to its normal diameter as would rubber, but upon dehydration does tend to seek its smallest 35 normal diameter dry.

The invention provides new and improved means for applying sealing bands rapidly and neatly in position on the necks of bottles. The invention is positive and efficient in operation, is 40 strong and durable in construction, and can be readily and economically manufactured. The device can be operated manually as shown in Figs. 1 to 6 or the same device can be applied to a rotary wheel and tripped by a stationary 45 cam. The invention however in either of its forms materially assists in the application of wet bands about the necks of bottles and prevents the revenue stamps or seals from becoming mutilated where such stamps or seals are required.

50 Changes may be made in the form, construction and arrangement of the parts of the apparatus and the method may be varied within certain degrees without departing from the 55 spirit of the invention or sacrificing any of its advantages, and the right is hereby reserved to make all such changes as fairly fall within the scope of the following claims.

What I claim as new and desire to obtain by 60 Letters Patent of the United States is:

1. In a device of the class described comprising an instrumentality to support a band about an outer surface thereof, means for spreading the band to provide an opening within the band 65 to receive the neck of a container, and means for releasing the spreading operation of said instrumentality whereby the said instrumentality may be readily withdrawn and the band will be positioned about the neck of the bottle.

70 2. In a device of the class described comprising an instrumentality to support a band about an outer surface thereof, means for spreading the instrumentality to spread the band to a predetermined shape to place the band about a bottle neck, and means for collapsing the instrumen-

tality whereby the said instrumentality will engage the bottle neck with the band about the instrumentality, said instrumentality being capable of being withdrawn bodily from between the band and neck and leave the band about the 5 neck.

3. In a device of the class described comprising an instrumentality to support a band about an outer surface thereof, means for spreading the instrumentality to spread the band and apply a 10 tension on the band, and for holding the said instrumentality in spread position while under tension of the band whereby a bottle neck may be received, means for releasing the instrumentality and causing the same to collapse about a 15 bottle neck, said band being arranged about the said neck when the instrumentality is withdrawn after being collapsed.

4. A device for applying bands to bottle necks comprising a pair of jaws adapted to receive a 20 band thereabout, means for spreading the jaws to hold the band in a predetermined position to provide an opening to receive the neck of a bottle, and means for closing the jaws whereby the band will be positioned exteriorly of the 25 jaws and the jaws between the neck of the bottle and the band, said jaws, when collapsed, being free to be removed from between the band and bottle whereby the band will be in position about the neck of the bottle. 30

5. A device for applying bands to bottle necks comprising a pair of jaws adapted to receive a 35 band thereabout, means for spreading the jaws to hold the band in a predetermined position to provide an opening to receive the neck of a bottle and to tension the said band and controlled by the tension of said band for maintaining the jaws in spread position, and means for closing the jaws whereby the band will be positioned exteriorly of the jaws and the jaws 40 between the neck of the bottle and the band, said jaws, when collapsed, being free to be removed from between the band and bottle whereby the band will be in position about the neck of the bottle. 45

6. A device for applying bands to bottle necks comprising a pair of jaws adapted to receive a 50 band thereabout, means for normally urging said jaws together, means for spreading said jaws against the action of said urging means to hold the band in a predetermined position and providing an opening to receive the neck of a bottle, said jaws when spread applying a tension on said band, said spreading means being held in active 55 position by the tension of the band to maintain the jaws in spread-apart position against the action of the urging means, and tripping means for closing the jaws whereby the band will be positioned exteriorly of the jaws and the jaws will be between the band and the neck of the 60 bottle, the collapsing of the jaws permitting the jaws to be removed from between the band and the bottle at which time the band will be positioned about the neck of the bottle. 65

7. In a device for applying bands about the 70 necks of bottles comprising a pair of jaws, means for normally holding the jaws in collapsed position, said jaws being adapted to receive a band thereabout, means for spreading the jaws a predetermined distance apart whereby a bottle neck may be received within the jaws, and means for returning the jaws to collapsed position whereby the jaws will be between a bottle neck and the band, said jaws being removed bodily from said 75

- in-between position leaving the band about the neck of the bottle.
8. A device for applying bands about the necks of bottles comprising a pair of jaws, spring means for normally urging the jaws together toward collapsed position, said jaws being adapted to receive a band thereabout, means for spreading the jaws apart a predetermined distance and against the tension of the spring whereby a bottle neck will be received between said jaws, said jaws when spread applying a tension to said band, said spreading means being held in active position by the tension of the band to maintain the jaws apart against the action of the spring means whereby an opening is provided to receive the neck of a bottle between the spread jaws, and trip means adapted to be operated by a part of the bottle to cause said spring means to return the jaws to collapsed position.
9. In a device for applying bands about the necks of bottles, a plurality of jaws adapted to receive a band thereabout, and toggle mechanism operable past dead center position for spreading said jaws to tension the band, the tension of the band serving to maintain the toggle mechanism in operated position.
10. In a device for applying bands about closures on containers comprising a movable element, a plurality of jaws carried by said movable element and adapted to be brought into position successively, said jaws being adapted to receive a band as the jaws are successively moved to

position, means for spreading the jaws when a band is thereabout, means for holding the jaws in spread position, and means operated by a bottle to move the jaws to collapsed position.

11. In a device for applying hydrated, regenerated cellulose bands to bottle necks, comprising a rotary element, means for receiving a band, means for spreading the band receiving means to spread the band whereby an opening is provided to receive the neck of the bottle, and means for collapsing said band receiving means to place the band about the neck of the bottle.

12. In a device for applying hydrated, regenerated cellulose bands to bottle necks, comprising a rotary element a plurality of jaws mounted on said rotary element, said jaws being adapted to receive a band thereabout, means for spreading the jaws with a band thereabout, and means controlled by a bottle for collapsing the jaws to place the band about the neck of a bottle.

13. In a device for applying bands about the necks of bottles, a plurality of jaws adapted to receive a band thereabout, toggle mechanism operable past dead center position for spreading said jaws to tension the band, the tension of the band serving to maintain the toggle mechanism in operated position, and means engageable with a portion of the bottle assembly for releasing said toggle mechanism.

HALLWARD F. NYGARD.
